(57) **CLAIM**

I claim the ornamental design for an earring, as shown and described.

DESCRIPTION

FIG. 1 is a front, top, and left side perspective view of an earring showing my new design;

FIG. 2 is a rear, bottom, and right side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof; and,

FIG. 9 is a referential view showing the article in use.

The broken lines in FIG. 9 depict environmental subject matter only and form no part of the claimed design.

1 Claim, 9 Drawing Sheets
